RETARDED SELF-CLOSING VALVE

James F. Molloy, Oakland, Calif.

Application February 28, 1941, Serial No. 380,976

4 Claims. (Cl. 137—139)

This invention relates to retarded self-closing valves and more particularly to water faucets.

Among the objects of the invention is the provision of means for utilizing the service pressure to open and close the valve.

Another object is the provision of a valve that may be opened with minimal manual effort, and that will automatically close after a lapse of time.

Another object is to conform to the conventional external design of valves, and particularly to lavatory faucets.

Another object is the provision of an improved external mechanism that may be substituted in appropriate types of valve bodies now installed.

A further object is the provision of a valve that may be opened with a light manual touch, regardless of the service pressure, and that will close without water hammer or other destructive reactions.

Other objects and advantages will appear as the description progresses.

In the one sheet of drawings the figure is a vertical section of a lavatory faucet constructed in accordance with this invention.

In detail the construction illustrated in the drawing comprises the valve body 1, having the threaded inlet neck 2 extending below the flat base 3. The neck is provided with the running nut 4 by means of which the faucet may be installed on a wash basin, in the usual manner.

In the present instance the body has the transverse partition 5 with a central opening with a tapered seat at 6. The discharge spout 7 extends outwardly from the body above the partition 5. The upper portion of the body is closed by the annular sleeve 8 threaded on the externally threaded top 9 of the body. This top portion 9 is internally bored to form the concentric guide 10, extending inwardly of the body 1.

The sleeve 8 is counterbored at 11 to form the chamber 12, beneath the concentric guide 13 extending above this chamber, and of less diameter than the chamber. The stem 14 is concentrically centerbored at 15 to the bottom 16 and has the external flange 17 slideable within the chamber 12. The top 18 of the stem is threaded into the push handle 19 that is counterbored at 21 to telescope freely over the concentric top 20 of the sleeve.

The cylindrical valve housing 22 snugly fits within the guide 10 and its lower end is shaped to make a water tight fit with the seat 6. Except for convenience in fabrication and replacement this housing is functionally a part of the partition 5 and may be connected therewith in

any suitable manner. The bottom 23 of this housing is internally recessed at 24 to form the valve seat 25, for the resilient valve 26 fixed in the lower end of the independent valve piston 27, that is freely slideable within the cylindrical bore 28 of the housing 22. The bottom 23 is provided with a plurality of longitudinal holes such as 29 extending therethrough.

The walls of the housing 22 are preferably of sufficient thickness to permit the boring of the by-pass hole 30 longitudinally thereof from the top to near the bottom 23. This by-pass has a lateral hole 31 extending from the counterbore 24 through the wall of the housing and into the space within the body 1 above the partition 5. There are three or more of these lateral holes such as 32, that are interspaced with the vertical holes 29.

The upper end of the housing is counterbored at 33 to receive the plug 34 that has a vertical flange 35 snugly fitting within the cylindrical center bore 28 of the housing. The upper end of this plug lies beneath the shoulder 36 of the sleeve 8, by which the housing is pressed against the seat 6. This plug has the vertical neck 37 extending upwardly into the center bore 15 from which it is concentrically spaced. This neck is internally threaded to receive the spring seated valve assembly inclusively designated by the number 38 and sealed within the neck 37. It has a seat for the valve 39 on the end of the spring urged plunger 40 extending above the neck 37 and into contact with the bottom 16. This valve assembly 38, just described, is similar to the conventional Schrader air valve used in pneumatic tires.

This invention operates substantially as follows: The valve at 26 is normally closed by the service pressure in the chamber 41 beneath the closed valve 39. When the handle 19 is depressed the shoulder 21 stops against the neck 31, and the pressure is instantly released through the valve 39, and the piston 27 is forced upwardly against the plug 34, by the inrush of pressure through the holes 29. The fluid flows beneath the valve 26 and escapes through the recess 24 and the outlets 31, 32, and is delivered through the spout 7. All the water escaping through the valve 39 is syphoned out of the chamber 12 and the by-pass 30 by the aspirating effect of the tubular nipple 31' in the outlet 31 acted upon by the kinetic energy of the fluid flowing through the spout 7.

Simultaneously with the closing of the valve 39, the flowing fluid starts seeping upward past

the piston 27 into the chamber 41 and the piston 27 begins to descend. The superficial area of the top of the piston being greater than the area of the valve opening at 25, the built up pressure gradually reseats the valve 26 and stops the flow. The delayed descent of the piston 27 determines the period of the cycle between the opening of the valve 39 and the closing of the valve 26. This period may be predetermined by the capacity of the chamber 41. If it is desired to shorten the interval of the cycle, displacement discs may be introduced above the piston or the capacity of the chamber 41 may otherwise be lessened.

If a continuous flow is desired through the spout 7, the handle 19 is held down, which maintains a constant flow through the valve 39 and prevents the building up of the closing pressure in the chamber 41.

Having thus described this invention what is claimed and desired to secure by Letters Patent is:

1. A valve in the class described including a body having a partition therein and an inlet and an outlet on opposite sides of said partition respectively; a valve housing rising from said partition and having an internal chamber closed at both ends except for an inlet and an outlet at the top and bottom respectively; and having a recess with a side outlet through the wall of said housing and communicating with a by-pass extending longitudinally through said wall and leading to an enclosed space in the body above said housing; a spring urged valve in said space controlling the top outlet from the chamber in said housing; external means for operating said valve; and an independent valve guided in said chamber and adapted to close said recess.

2. A valve in the class described including a body having a partition therein and an inlet and an outlet on opposite sides of said partition respectively; a valve housing rising from said partition and having a chamber therein with an inlet through said partition; a plug closing the top of said chamber and having a hollow neck open to said chamber; a sleeve engaging the top of said body and bearing against said plug; a spring urged valve in said neck and having a protruding plunger; handle means engaging said plunger;

5 er; a valve seat in the bottom of said housing and having a recess thereunder with a lateral outlet above said partition and communicating with a by-pass leading to the space above said plug; and a valve piston slideable within said chamber and cooperating with the said valve seat therein.

3. A valve in the class described including a body having a partition therein and an inlet and an outlet on opposite sides of said partition respectively; a valve housing rising from said partition and having a chamber therein with an inlet through said partition; a plug closing the top of said chamber and having a neck with a counterbore therethrough open to said chamber; a hollow stem telescoping over said neck and having an annular flange thereon; a sleeve engaging the top of said body and having an annular shoulder overhanging said plug and a counterbore slideably guiding said stem and a shoulder engaging said flange; a spring seated valve in said neck and having a plunger engaging the bottom end of the counterbore in said stem; a valve seat in the bottom of said housing and having a recess thereunder with a lateral outlet above said partition and communicating with a by-pass leading to the space above said plug; and a valve guided in said chamber within the housing and cooperating with said valve seat.

25 4. A valve in the class described including a body having a partition therein and an inlet and an outlet on opposite sides of said partition respectively; a valve housing rising from said partition and having an internal chamber closed at both ends except for an inlet and an outlet at the bottom and top respectively and having a recess with a plurality of side outlets through the wall of said housing and communicating with a bypass leading to an enclosed space in the body above said housing; an aspirating means interposed between one of said side outlets and said bypass; a spring urged valve in said space controlling the top outlet from the chamber in said housing; external means for operating said outlet valve; and an independent valve piston guided in said chamber and adapted to close said recess.
